UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL-ANCHOR.

1,376,490.

Specification of Letters Patent.

Patented May 3, 1921.

Application filed September 27, 1919. Serial No. 326,855.

To all whom it may concern:

Be it known that I, HAROLD G. WARR, a citizen of the United States, residing at Park Ridge, in the county of Cook and State of Illinois, have invented certain new and useful Improvements in Rail-Anchors, of which the following is a specification.

My invention relates to rail anchors, that is to say, to devices for checking the tendency of railroad rails to move longitudinally due to the passing of traffic in one general direction, or other causes, and particularly to the type of rail anchor involving the attachment of the device to the web of the rail by a pin bolt or other fastening device; and the invention has for one of its objects to provide a device of this character which will be light, strong and inexpensive to manufacture.

A further object of the invention is to so construct a rail anchor of this type that its grip on the rail is not lessened by any tendency of the anchor to twist or rotate on a vertical axis, under a forward stress on the rail, under conditions producing such loosening. Preferably the construction is such that the forward stress on the rail tending to produce such a rotational movement operates to tighten the device on the rail. This construction also minimizes the pressure on the fastening bolt or pin, and thereby lessens the chance of the bolt or pin being sheared off or broken under this creeping stress.

A further object is to provide a rail anchor of the type indicated which can be used on either side of a rail against any tie to prevent creeping in the direction in which the rail in question tends to creep.

The invention is illustrated in the accompanying drawings, wherein—

Figure 1 is a plan view of a device constructed in accordance with my invention applied to a railroad rail, the web of the rail being shown in section.

Fig. 2 is a side view of the structure shown in Fig. 1.

Fig. 3 is a sectional view taken on line 3—3 of Fig. 2.

Fig. 4 is a blank from which the anchor is formed.

Fig. 5 is a view, in perspective, of the anchor shown in the preceding figures.

Fig. 6 is a view similar to Fig. 1, illus-

trating a modified and improved form of anchor.

Fig. 7 is a side view of the same, and

Fig. 8 illustrates the blank from which this form of anchor is made.

Like characters of reference designate like parts in the several figures of the drawings.

Referring first to Figs. 1 to 5 inclusive, of the drawings, 10 designates a railroad rail and 11 one of the cross ties on which the rail is supported. The anchor shown in these figures is a one-piece device consisting, in effect, of a rail engaging shoe, an attaching web adapted to be fastened to the vertical web of the rail, and a tie-abutting plate 70 or flange. It is made from a single, integral sheet metal blank 12 having the configuration shown in Fig. 4. The upper end 13 of the blank is bent along the line 14 so as to provide an upstanding portion or attaching web 15 which is secured to the web 16 of the rail. This portion of the anchor is preferably formed with a slight curve corresponding to the contour of the web 16 and is secured to the web by means of a pin 17 which extends through holes 18, 19 drilled in the anchor and rail web, respectively. Any other suitable fastening device might be used. The portion 20 of the blank is bent downwardly on the line 21 so as to provide a vertical bearing surface 22 which engages the vertical edge of the rail. The portions 23, 24 of the blank are bent inwardly on the lines 23^a, 24^a, so as to provide a tie-abutting member and also, in effect, a double jaw 25 or pair of jaws (Fig. 5) which engage both the upper and lower surfaces of one of the base flanges of a rail. It will be seen that the anchor, being formed with two vertical flanges 23, 24, which extend under the rail base, may be applied to either side of the rail against the same face of one of the ties on which the rail is supported. The devices, in other words, do not have to be made in rights and lefts.

When the anchor is in its operative position as shown in Figs. 1, 2 and 3, any creeping action of the rail in the direction indicated by the arrow in Fig. 1 forces the tie-abutting web 23 of the anchor against the tie 11. This pressure has a tendency to slightly rock the anchor on its horizontal pivot 17, in the direction indicated by the

arrow in Fig. 2, and produces an increased pressure between the under surface of the portion 26 of the anchor, bearing against the upper surface of the rail, and the upper edge 27 of the flange 24, bearing against the under surface of the rail. This increased grip of the anchor, in addition to resisting the creeping pressure, relieves the shearing stress on the rivet 17.

10 In Figs. 6 to 8 inclusive, I have shown a modified and improved form of anchor which is designed to accomplish the second of the above mentioned objects. In this form of device the attaching web 29 of the 15 anchor extends toward the tie 11 and is riveted or otherwise secured to the vertical web 16 of the rail at a point in line with or preferably slightly in advance of the forward vertical edge 34 of the jaw portion 20 of the anchor.

This device is also preferably, but not necessarily, made from a single sheet metal blank which is cut or bent to provide in addition to the attaching web 29 mentioned, 25 a shoe portion 30 bearing on the upper surface and outer edge of the rail base and flanges or plates 31, 32, the upper edges of which engage the under surface of the rail base, one of said flanges bearing against the 30 tie. The device is fastened to the rail web by a suitable fastening device, such as bolt 33 shown in the drawings.

In the form of device shown in Figs. 1 to 5 inclusive, there may be some tendency of the 35 anchor to rotate on a vertical axis passing through the point of attachment to the web of the rail since the bearing face on the tie is at one side of the point of attachment of the device to the web 16 of the rail, and 40 this rotation will necessarily tend to loosen the grip of the device on the rail base. This tendency to loosen through rotational movement cannot be altogether obviated by placing the bearing flange of the anchor under 45 the rail web, that is, in the center of the rail, because the tie will not always present a flat surface at right angles to the axis of the rail for the flange of the anchor to bear against. In the rail anchor as shown in 50 Figs. 6, 7 and 8, by arranging the point of attachment of the anchor to the web of the rail in a vertical plane passing through the forward edge of the jaw portion of the anchor there will be no loosening effect resulting 55 from the tendency of the anchor to rotate on a vertical axis even though the bearing face of the anchor on the tie is at one side of the rail web. By having the point of attachment 33 in advance of point 60 34, in accordance with the preferred arrangement shown in these figures—with relation, of course, to the direction of the creeping movement of the rail—a rotational movement on a vertical axis or tendency to 65 such rotational movement results which

tightens the grip of the anchor on the rail base in proportion to the strength of the creeping stress. In order to make possible this tightening rotational movement a slight twist is preferably given to the web 29 resulting in clearances indicated at 35, 36 in Fig. 6, whereby any tendency of the anchor to rotate on a vertical axis will increase the wedging grip of the anchor on the upper and lower surfaces of the rail base.

70 While I have shown and described certain specific features in the construction of a rail anchor in accordance with my invention, it will be obvious that these constructions might be varied in certain respects without departing from the principle of my invention. I therefore do not wish to limit myself to the particulars shown and described, except in so far as specific limitations may appear in the appended claims.

75 80 85 1 claim:

1. A one-piece sheet metal rail anchor cut and bent to provide a shoe member having a tie abutting portion and an upstanding member adapted to be secured to the vertical web 90 of a rail, whereby lateral movement of the device, resulting from the creeping pressure of the rail, will increase its grip on the rail.

2. A one-piece sheet metal rail anchor cut and bent to provide a shoe member having a 95 pair of inwardly projecting flanges at opposite ends providing bearing surfaces adapted to grip the under surface of the rail, one of which flanges is adapted to lie against a tie, and an upstanding member adapted to 100 be secured to the vertical web of a rail.

3. A rail anchor comprising a jaw portion 105 for engaging the base flange of a rail, means for bearing against a tie at one side of the center of the rail, and a member for attachment to the vertical web of the rail at a point close to a vertical plane passing through the forward edge of the jaw portion of the anchor, whereby a forward creeping stress on the rail tending to rotate the 110 device on a vertical axis increases the grip of said jaw on the rail base.

4. A rail anchor comprising a jaw portion 115 engaging the base flange of a rail, means for bearing against a tie at one side of the center of the rail and a member for attachment to the vertical web of the rail at a point in advance of a vertical plane passing through the forward edge of the jaw portion of the anchor, whereby a forward creeping 120 stress on the rail produces a rotational movement of the anchor on a vertical axis which tends to increase its grip on the rail base.

5. A one-piece sheet metal rail anchor, cut and bent to form a rail base engaging shoe 125 provided with a pair of flanges adapted to engage the under surface of the rail base and one of which is adapted to bear against a tie, and provided further with an upstanding web, having a perforation for attach- 130

ment to the web of the rail, which upstanding web projects forwardly, with relation to the direction of the creeping stress on the rail, to a point at or beyond the rail engaging portion of the anchor.

6. A rail anchor having a rail engaging portion for engaging one side of the base flange of a rail, a tie engaging portion adapted to bear against a tie on one side of the rail and an upwardly projecting member provided with means for attaching to the upstanding web of the rail at a point forward of (having reference to the direction of the creeping stress on the rail) the rail engaging portion of the anchor.

7. A rail anchor formed with a jaw adapted to engage one side of the rail and to bear against a tie on one side of the center of the rail, and means for attaching the device to the rail in advance of the point of en-

gagement of said jaw so that the forward creeping tendency of the rail produces a tightening rotational movement of the anchor thereon.

8. A rail anchor provided with means for attaching it to the rail and adapted to engage the rail and bear against the tie so that a forward creeping movement of the rail tends to produce a rotational movement of the anchor on a vertical axis which increases the grip of the anchor on the rail.

9. A rail anchor which in use engages one side only of the rail and is formed with two oppositely placed surfaces for bearing against a tie so that it may be used either on the right or left hand side of a given rail, having reference to the direction of the creeping stress.

HAROLD G. WARR.
